Friedrichshafen

UNITED STATES PATENT OFFICE.

SAMUEL S. VINEBERG, OF WINNIPEG, MANITOBA, CANADA.

SAFETY HANGER.

Application filed June 23, 1923, Serial No. 647,368, and in Canada February 12, 1923.

The invention relates to improvements in safety hangers and particularly to a hanger for supporting hats, caps, coats and such like garments, and an object of the invention is to provide a hanger which can be locked to prevent the removal of the hats or garments suspended or hung from the hanger.

A further object is to construct the device such that it is key controlled and such that the one hanging the garments or hats on the hanger can lock the same on the hanger and take the key away with him and upon returning can unlock them and after having unclosed them cannot remove the inserted key.

A further object is to construct the appliance such that it cannot become locked unless a hat or garment, or such like, is suspended therefrom.

A still further object is to construct a device particularly for use in hotels, restaurants, and other public buildings.

A further object is to construct the article such that it will have a pleasing appearance and so that it can be manufactured at comparatively small cost.

With the above more important objects in view the invention consists essentially in the arrangement and construction of parts hereinafter more particularly described and later pointed out in the appended claims, reference being had to the accompanying drawing in which:

Fig. 1 is a perspective view of the complete hanger.

Fig. 2 is an enlarged detailed vertical sectional view centrally through the hanger.

Fig. 3 is an enlarged detailed horizontal sectional view at 3—3' Fig. 2 and showing the key turned one quarter of a revolution.

Fig. 4 is a face view of the upper end of the hanger and showing the key inserted.

In the drawing like characters of reference indicate corresponding parts in the several figures.

The back or body 1 of the hanger is in the form of an elongated metallic plate provided with suitable openings whereby the same can be fastened by screws 2, or such like, to a wall or rack. At the upper end the plate is provided with a housing 3 for working parts later described and at the lower end it is provided with a hook 4 and beneath this with an outstanding post 5. In the present

instance the hook and post are cast as an integral part of the plate. Between the hook and the housing 1 locate a hat hook or post 6 which is adapted to support a hat, cap, or such like placed thereon. It is pointed also that the hook 4 is located above the post 5 and is positioned such that upon a coat or similar garment being suspended from the said hook the material of the coat will naturally hang down over the outer end of the post 5. A locking lever 7 is provided, the locking lever having the upper end entering the housing and pivotally connected thereto by a pivot pin 8. The lever presents an outstanding arm 9 and a downwardly extending arm 10, the arm 10 being offset towards the lower end and terminating in a handle 11. In its lower position the lever normally engages the outer ends of the posts 5 and 6, as best shown in Figure 2.

Within the housing 1 locate a cross shaft 12 which, in the present instance pivotally supports two rocking arms 13 and 14 and a locking catch 15. In the horizontal position the rear ends of the rocking arms are adapted to engage with a stationary cross bar 16 passing across the housing, being pulled towards the bar by suitable springs 17 and 18.

The rear end of the short arm 13 is provided with a down hanging pivoted substantially L-shaped leg 19, the lower end of which is adapted to engage with and ride the upper hooked end 20 of the lever 7, and the catch 15 is adapted under certain conditions, as later explained, to engage the hooked end 20 of the lever and lock the same against movement. The catch 15 is normally pulled towards the hooked end of the lever by a coiled spring 21.

The rear end of the rocker arm 14 is connected to a vertically disposed shifting bar 22 which passes down centrally behind the plate 1 in a suitable recess or slot 23 provided.

A pin 24 is slidably mounted in the post 6 and a further pin 25 is slidably mounted in the post 5. The rear ends of these pins are pivotally connected to bell cranks 26 and 27 pivotally mounted behind the plate 1 and the bell cranks are pivotally attached to the bar 22, the arrangement being such that in the in or back shifting of the pins the bar 22 rises. Normally the forward ends of the pins protrude beyond the forward ends

of the posts and they are adapted to enter pockets 28 and 29 provided in the arms 7 (see Fig. 2).

A key 30 is supplied to control the rocker 5 arms and catch, the key being inserted through a suitable sleeve 31 provided, and being fitted at the outer end with a notch 32 which is adapted to receive the edge of a keeper plate 33 located at the forward end 10 of the sleeve. A slot 34 is provided in the keeper plate, which allows the key to enter and after it has entered in a flat lying position and has been turned to the vertical position as shown in Fig. 4 it cannot be re- 15 moved owing to the fact that the edge of the keeper plate is in the notch 32.

The key is provided with a slot 35 for the arm 14, a slot 36 for the arm 13, and a projecting tongue or striker 37 for the catch 20 15, it being here observed that the said catch is provided with an extending arm 15'.

Normally the parts are in the unlocked position as shown in Fig. 2, the key being 25 in place and in the vertical position as shown. Here it will be observed that the tongue 37 of the key is engaged with the arm 15' of the catch 15 and that the said catch by such engagement is held clear of the 30 hooked end of the lever 7.

Upon a party desiring to place his hat and coat on the hanger he simply grasps the handle end of the lever and pulls it outwardly or ahead sufficient to allow him to 35 place his hat and coat on the posts 6 and 5. Having done this he then shoves the handle 7 back towards said latter posts, the material of the hat and the coat then being between the posts and the lever 7. 40 The material of the hat and coat causes the pins 24 and 25 to be moved inwardly and held inwardly, which action swings the forward end of the arm 14 down and holds it down. As the lever 7 is in the closed 45 position the inner end of the arm 13 is held down. After the party has placed his hat and coat on the posts and has closed the lever he then turns the key to the right to bring it to the horizontal position; in so doing 50 he turns down the tongue 37 and the arm 15' following it allows the catch 15 to engage the hooked end of the lever 7 and consequently lock it against movement. The hat and coat accordingly cannot be removed 55 and as the inner ends of the arms 13 and 14 have been brought to a position where they are entirely clear of the slots 35 and 36 in the horizontal position of the key, the key can be removed. The party then can 60 go about his business. Upon returning he inserts the key and turns it to its vertical position and in so doing releases the catch 15, thereby unlocking the lever 7 and permitting him to swing it outwardly and remove his hat and coat. After he has re- 65

moved his hat and coat the spring 17 resets the pins 24 and 25 into the position shown in Figure 2, by its action on the arm 14, and it also brings the arm 14 to the horizontal position. The key cannot thereafter 70 be removed for the reason that if it be brought at this time to the horizontal position, whereby it could be withdrawn through the slot 34, it will be found that the inner end of the arm 14 is in the slot 35 of the key. 75 This feature is important as it prevents the key being taken away after the party has removed his hat and coat. As an actual fact when the party has the key his apparel is locked on the hanger and when he has 80 his apparel the key is in place on the hanger and cannot be removed. It is also pointed out that when the lever 7 is unlocked and opened the inner end of the arm 13 also enters the slot 31 and prevents the removal 85 of the key.

Whilst I have explained the above operation where both a hat and a coat are hung on the posts, the article works just the same with either a hat, coat, or other garment, 90 as, from the disclosure, it will be apparent that the placing of a hat on the post 6 will be all that is necessary to actuate the pin 24 upon the lever 7 being closed, whilst if it be placed on the post 5 the pin 25 will be 95 shifted by the action of the lever. The shifting of either pin results in the required movement of the bar 24.

Whilst I have entered into a detailed description of the various parts it will be 100 readily understood that I do not wish to be limited to the precise construction shown as this might be modified without departing in the slightest from the spirit of the invention as set forth in the retained claims. 105

What I claim as my invention is:

1. A hanger for supporting wearing apparel, comprising a support for the apparel and key controlled means releasably locking the apparel on the support, and means operated by the removal of the garment, for locking the key when the garment is removed from the support. 110

2. A safety hanger for wearing apparel, comprising a stationary extending post for supporting the apparel, a pivoted lever adapted to pass across the end of the post and jam the apparel hung thereon between the lever and the post and a key controlled means for locking the lever in such latter position, and means operated by the removal of the garment, for locking the key when the garment is off the post. 115

3. A safety hanger for wearing apparel, comprising a stationary extending post for supporting the apparel, a pivoted lever adapted to pass across the end of the post and jam the apparel hung thereon between the lever and the post, and a key controlled lock for locking the lever in such latter position, 120

125

and means operated by the removal of the garment, for locking the key when the garment is off the post.

4. A safety hanger for wearing apparel, comprising a post supporting the apparel, a pivoted lever adapted to cross the end of the post and to the outer side of the apparel suspended by the post, a key controlled lock for locking the lever against movement in the latter position, a sliding pin mounted in the post and shiftable endwise, said pin being actuated by the apparel suspended from the post and under the influence of the lever and connections associated with the pin and key, whereby upon the lever being locked the key can be removed, and in the unlocked condition of the lever the key cannot be removed.

5. A safety hanger comprising a permanently mounted body plate presenting a garment supporting post and a housing above the post, a substantially L-shaped lever having the upper end pivotally mounted and terminating within the housing and the lower end normally crossing the free end of the post, a pivoted spring pressed catch contained within the housing and engageable with the upper end of the lever and adapted when engaged to lock the lever against movement, and a key insertible within the housing and engageable with the catch for unlocking the same.

6. A safety hanger, comprising a permanently mounted body plate presenting a garment supporting post and a housing above the post, a substantially L-shaped lever having the upper end pivotally mounted and terminating within the housing and the lower end normally crossing the free end of the post, a pivoted spring pressed catch contained within the housing and engageable with the upper end of the lever and adapted when engaged to lock the lever against movement, a rocker arm pivotally mounted within the housing, a pin slidably mounted within the post and having one end thereof normally protruding beyond the end of the post and housed within a pocket provided in the lever, a connection between the inner end of the pin and the rocker arm adapted, upon the shifting of the pin, to lower one end of the rocker arm, and a key insertible within the housing and engageable with the catch and the rocker arm, said rocker arm permitting of the insertion of the key upon the pin being pressed inwardly by the apparel under the influence of the lever and preventing the removal of the key when the pin is extended within the pocket of the locking lever, and said catch being adapted to lock the locking lever by contact with the inserted key.

Signed at Winnipeg, this 22nd day of February 1923.

SAMUEL S. VINEBERG.
